UNITED STATES PATENT OFFICE.

NATHANIEL L. HURD, OF CHICAGO, ILLINOIS, ASSIGNOR TO SAMUEL M. LANGSTON COMPANY, OF CAMDEN, NEW JERSEY, A CORPORATION OF NEW JERSEY.

SLOTTING AND SCORING DEVICE.

Application filed April 23, 1923, Serial No. 633,866. Renewed December 16, 1924.

To all whom it may concern:

Be it known that I, NATHANIEL L. HURD, a citizen of the United States, residing at Chicago, in the county of Cook and State of Illinois, have invented certain new and useful Improvements in Slotting and Scoring Devices, of which the following is a specification.

This invention relates to a device for slotting and scoring material such, for example, as box-board for the manufacture of corrugated boxes.

One object of the invention is to provide simple, reliable and efficient means for slotting and scoring box-board material and which requires a minimum number of adjustments and assures accurate results.

In combined slotting and scoring heads it has been proposed to provide one head 20 of each pair with a pair of slotting blades spaced apart to a distance equal to the length of the box for which the blank is to be formed, and mount between these blades a scoring member. The blades are usually 25 made adjustable toward and from each other circumferentially of the head to facilitate the forming of blanks for boxes of different lengths, and this necessitates the provision of a different length of scoring 30 member for each box length.

One object of my invention is to so construct and mount the scoring member that a single member will serve for all box lengths and may have its effective length varied to adapt it to any desired spacing of 35 the slotting blades.

In carrying out my invention I employ a flexible or articulated scoring member, and so design the head that a portion of said 40 member may be stored or mounted in inoperative position within the head, and may be drawn out into operative position on the periphery of the head to thereby vary the length of the effective or operating portion.

Such a flexible or articulated scoring member is disclosed and broadly claimed, and one form is specifically claimed in my copending application Serial No. 720,924, 50 filed June 19, 1924, while in the present application I claim the combined slotting and scoring construction and also claim a different form of scoring member.

In the accompanying drawings I have 55 shown certain embodiments of my inven-

tion which are to be considered in an illustrative rather than a limiting sense, as various changes may be made within the scope of my invention and defined in the appended claims.

60

In these drawings:

Figure 1 is a side elevation of a machine which is ordinarily used for slotting and scoring box-board;

Figure 2 is a fragmentary front elevation 65 of the same;

Figure 3 is a side elevation of a pair of cooperating combined slotting and scoring members embodying my invention;

Figure 4 is a sectional view of the same 70 taken in the plane of line 4-4 of Figure 3;

Figure 5 is a fragmentary sectional view taken in the plane of line 5-5 of Figure 3;

Figure 6 is a fragmentary side elevation 75 of another pair of cooperating members embodying my invention and adapted to score material along lines which are offset with respect to each other;

Figure 7 is a diagrammatic view of a completed box blank, the transverse slotting and scoring of which is done by means of the cooperating members shown in Figures 3, 4 and 5;

Figure 8 is a fragmentary end view of 85 one of the heads shown in Figure 6 and showing the stationary scoring members in offset relationship to make offset scores shown in Figure 9; and

Figure 9 is a diagrammatic view of a 90 completed box blank showing scoring along longitudinal lines which are offset with respect to each other for facilitating folding and sealing of the flaps for avoiding strain at the corners of the box.

95

The various novel features of the invention will be apparent from the following description and drawings and will be particularly pointed out in the appended claims.

Referring first to Figures 1 and 2 of the 100 drawings, it will be noted that there is shown a machine which ordinarily is used for slotting and scoring corrugated box-board for the manufacture of corrugated boxes. With this machine the slotting is done by pairs of 105 cooperating revolving members or heads 10 and 11 mounted, respectively, upon driven shafts 12 and 13. One member 10 of each set is provided with a segmental knife 14 which registers with a corresponding groove 15 in 110

the associated member 11. In this same machine the scoring is done by sets of scoring wheels, each set including a scoring wheel or head 16 and a cooperating scoring wheel 5 or head 17 having peripheral formations for accomplishing the desired result. These scoring wheels 16 and 17, respectively, are mounted on other shafts 18 and 19, respectively.

10 It will be appreciated that a single machine is used for slotting and scoring blanks to be made up into boxes of various sizes. In order to change the adjustment of this machine for slotting and scoring blanks for 15 one size of box to another, it is necessary, with the type of machine shown in Figures 1 and 2, to adjust three sets of slotting heads and three sets of scoring wheels, and in view of the fact that the slotting heads and scoring 20 wheels are not on the same shafts, it very often happens that the scores 20, as shown, for example, in Figure 7, are not in line with the associated slots 21.

In order to decrease the number of 25 adjustments necessary and to insure the proper location of the score with respect to slots, and generally to improve devices of this nature, the slotting and scoring members are combined in single cooperating units. This 30 may be accomplished, for example, by means of the arrangement shown in Figures 3, 4 and 5 wherein there are disclosed two cooperating slotting members 22 and 23 also embodying scoring means. These members 35 22 and 23 are secured to shafts 24 and 25, respectively. The head 22 is provided with a curved or arcuate shaped slotting knife 26, which is fixed within the head and cooperates with a slotting groove 27 in head 23 40 for performing a slotting operation. As shown in Figure 7 the slots 21 lying along the same line, are spaced from each other a predetermined amount. In a blank for a different sized box, the slots along the same 45 line may be spaced a different amount. Accordingly, another slotting knife 28 mounted in the head 22 is made circumferentially adjustable within said head so that the distance between the ends 29 and 30 of the slotting knives 26 and 28 may be varied in accordance 50 with requirements. The head 23 is provided with another groove 31 for cooperatively receiving the slotting knife 28.

Instead of having the scoring means in 55 a different set of heads, I have provided an arrangement whereby the scoring members may be mounted in the same heads 22 and 23. In view of the fact that the distance between the slots 21 in the same straight line 60 may be spaced variable amounts for boxes of different sizes, it is apparent that provision must be made for scoring variable distances. To accomplish this in a simple manner and to provide for a quick and easy adjustment, each head 22 and 23 is equipped

with a flexible scoring member. The flexible scoring member 32 which at one end may be secured to the movable slotting knife 28, extends through an undercut groove 33 in head 22 and the excess length of said scoring member extends into a suitable pocket 34 within the head 22. Similarly the flexible scoring member 35 associated with head 23 is adjustably mounted in an undercut slot 36 in the head 23, the excess length of said flexible scoring member being stored in pocket 37 within said head. These flexible scoring members 32 and 35 may be provided with any suitable scoring surfaces such, for example, as shown at 38 in Figure 4.

70 The slotting knives 26 and 28 and the scoring members may be secured in the heads by removable disks 39 which normally are secured to the heads by any suitable means such as bolts 40. While the scoring members occupy the undercut grooves in the heads, the slotting knives preferably are secured in an annular groove 41 in the disk 75 radially inwardly from undercut grooves. In view of the fact that the flexible scoring 80 members curve inwardly, as shown at 42, some supplemental scoring means must be provided in head 22 from the point where the flexible scoring member 32 curves inwardly to the end 29 of the slotting knife 26 and similarly some supplemental scoring 85 means must be provided from the point where the flexible scoring member 35 curves inwardly to the end 43 of slot 27. Such 90 scoring means takes the form of stationary 95 plates 44 mounted in said heads 22 and 23, respectively.

95 By means of this arrangement a corrugated boxboard blank may be accurately slotted and scored in a single operation. 100 By treatment between the members 22 and 23, the blank is provided with slots 21 and scores 20 extending along the same straight lines connecting said slots. The length of 105 the scoring between the associated slots 21 may be quickly varied in accordance with 110 requirements, by merely loosening the clamping disks, adjusting the scoring members 32 and 35 and movable knife 28 and again securing the clamp disks in position. Accordingly, a minimum number of parts require 115 adjustment and a minimum amount of time is required for making the adjustment, and the accuracy of such adjustment is assured.

120 In Figure 6 there is shown a pair of cooperating scoring members by means of which scores may be made in offset relation with respect to each other as shown, for example, in the diagram of a blank in Figure 125 9. In said diagram it will be noted that the scores 45 are along the same straight line and the scores 46 are along another straight line, said scores 45 and 46 being offset with respect to each other. It is appreciated that 130 box blanks have been scored in this manner

before but by means which are entirely different from that which I employ.

Referring particularly to Figure 6 it will be noted that two cooperating scoring heads 47 and 48 are provided in which a plurality of adjustable scoring members are mounted. In this particular instance there are four flexible and adjustable scoring members 49, 50, 51 and 52 in each head 47 and 48. In adjusting the scoring members in each head the same should be done from a central point. In this connection it will be noted that the distance between the inwardly curved portions of each of the scoring members 50 and 51 is spanned by stationary scoring members 53 and 54 which are offset with respect to each other to make the adjacent portions of the offset scores 45 and 46 between the points 55 and 56, as shown in Figure 9. The balance of the associated score 45 is made by the scoring members 50 and the balance of the associated score 46 is made by the scoring members 51. The right-hand score 45 in Figure 9 is made by scoring members 52 and the left-hand score 46 in Figure 9 is made by scoring members 49. The excess length of the scoring members 50 and 51 in each case is received in associated pockets 57 and 58 in said scoring heads.

It is apparent, therefore, that by use of the scoring mechanism shown in Figure 6, box blanks may be scored along lines which are offset with respect to each other in a simple, efficient and accurate manner and in a manner to meet all of the requirements for successful commercial use.

As shown in Figure 9 the box blank is provided with longitudinal scores offset on each alternate panel for the purpose of permitting one pair of flaps on top and bottom of the box to fold inside the outer flaps to prevent strain at the corners.

It is my intention to cover all modifications of the invention falling within the spirit and scope of the following claims.

I claim:

1. In a device for slotting and scoring box-board and the like, a plurality of cooperating members having complementary portions whereby slotting and scoring of the material may be done in a single operation, and supports for said members, the scoring members being flexible for curving same into said supports for storage of the excessive length thereof.

2. In a device for slotting and scoring box-board and the like, a plurality of cooperating members having complementary portions whereby slotting and scoring of the material may be done in a single operation, one of said members including an adjustable knife for slotting purposes and a flexible scoring member associated therewith.

3. In a device for slotting and scoring

box-board and the like, a plurality of cooperating members having complementary portions whereby slotting and scoring of the material may be done in a single operation, one of said members, including an adjustable knife for slotting purposes, a scoring member associated therewith, and means whereby the effective length of said scoring member may be varied.

4. In a device for slotting and scoring box-board and the like, a plurality of cooperating members having complementary portions whereby slotting and scoring of the material may be done in a single operation, one of said members including a relatively fixed and a relatively adjustable knife for slotting purposes, and an adjustable scoring member interposed therebetween whereby the length of the scoring and the distance between the slots are varied.

5. In a device for slotting and scoring box-board and the like, a plurality of cooperating members for slotting and scoring of material in a single operation, one of said members including a knife and the other member having a groove for the reception of said knife for slotting purposes, and both of said members having flexible cooperating scoring members whereby the material may be scored.

6. In a device for slotting and scoring box-board and the like, a plurality of cooperating members for slotting and scoring material in a single operation, one of said members including a plurality of knives and the other a plurality of cooperating grooves by means of which the material may be slotted, and both of said members having flexible cooperating scoring members whereby said material may be scored between the slots.

7. In a device for slotting and scoring box-board and the like, a head, a slotting member in said head, and a scoring member carried by said head whereby material may be slotted and scored in a single operation, the scoring member being flexible for curving same into said head for storage of the excess length thereof.

8. In a device for slotting and scoring box-board and the like, a supporting head, a plurality of slotting members mounted in said head, and a flexible scoring member interposed between said slotting members whereby material may be provided with a plurality of slotted portions and a scored portion therebetween.

9. In a device for slotting and scoring box-board and the like, a supporting head, a plurality of relatively adjustable slotting members mounted in said head, and a scoring member adjustable within said head and interposed between said slotting members whereby material may be slotted and scored in a single operation, said scoring of the

material being thereby variable in length.

10. In a device for slotting and scoring box-board and the like, a supporting head, a relatively stationary knife carried by said head, a movable knife adjustably mounted in said head, and a flexible scoring member between said knives whereby a blank may be slotted and scored in a single operation and the distance between the slotted portions varied.

11. In a device for slotting and scoring box-board and the like, a supporting head, a slotting member carried by said head, and a flexible scoring member associated with said slotting member and adjustably mounted in said head whereby a blank may be slotted and scored, the length of the score being variable.

12. In a device of the class described, a supporting head having a pocket therein, and a flexible scoring member carried by said head, one end portion of said flexible scoring member being received by said pocket.

13. In a device of the class described, a supporting head having a pocket, a flexible scoring member adjustably carried by said head, said pocket receiving excess length of the scoring member, and a relatively stationary scoring member for carrying a score directly to a slotted portion to compensate for the curved part of the scoring member passed into said pocket.

14. In a device of the class described, a supporting head having a pocket, a slotting knife carried by said head, a flexible scor-

ing member carried by said head which curves into said pocket, and a relatively stationary scoring member interposed between one end of said slotting knife and a portion of said flexible scoring member for the purpose of carrying the scoring to the slot made by said slotting knife.

15. A slotting and scoring head having an opening in the periphery thereof, a slotting blade movable circumferentially toward and from said opening, and a scoring member secured to said blade and extending along said periphery and movable into and out of said opening.

16. A combined slotting and scoring head having an opening in the periphery thereof, a slotting blade movable circumferentially of said head toward and from said opening, and a scoring member extending from said blade to said opening and movable along said periphery and through said opening.

17. A combined slotting and scoring head having an opening in the periphery thereof, a relatively stationary scoring member at one side of said opening, a slotting blade at the other side of said opening and movable circumferentially of the head toward and from said opening, and a scoring member between said blade and said opening and movable back and forth through said opening.

Signed at Chicago, Illinois, this 19th day of April, 1923.

NATHANIEL L. HURD.
